UNITED STATES PATENT OFFICE.

DAVID A. ST. CLAIR, OF WYTHEVILLE, VIRGINIA, ASSIGNOR TO G. REIS & BRO. INC.,
OF NEW YORK, N. Y., A CORPORATION OF NEW YORK.

FILLER-FORM FOR EMBROIDERY.

1,294,560.

Specification of Letters Patent. Patented Feb. 18, 1919.

Application filed July 14, 1914. Serial No. 850,968.

To all whom it may concern:

Be it known that I, DAVID A. ST. CLAIR, a citizen of the United States, residing at Wytheville, in the county of Wythe and 5 State of Virginia, have invented certain new and useful Improvements in Filler-Forms for Embroidery, and I do hereby declare the following to be a full, clear, and exact description of the same, reference being 10 had to the accompanying drawings, forming part of this specification, and to the figures and letters of reference marked thereon.

This invention relates to filler forms for 15 embroidery and has for its object the provision of a filler form which will retain its shape, even with the most delicate tracery, while the embroidery is being done, and which will, at the same time, give to the 20 finished embroidery the desirable well-rounded contour. Further objects of the invention are to provide a filler form which will expand after the embroidery is finished so as to take up any looseness in the embroidery 25 stitches and which will permit of the finished embroidery being washed an indefinite number of times without injury to its appearance.

Generally stated, the invention consists 30 in a filler form for embroidery designs made of an elastic and expansible fibrous material held in compression by a binding agent which is susceptible of being removed by washing or otherwise so as to permit the 35 elastic or expansible material to expand and fill out the embroidery stitches. More specifically, the invention consists in a filler form made of interlocked matted or felted fiber of an elastic nature, such, for example, 40 as cotton felt or batting, normally held in compression by a soluble binding agent, starch, for example, which may be readily removed by washing in ordinary water, whereby, after the embroidering is completed 45 the binding agent may be removed and the fiber material permitted to expand.

Referring to the accompanying drawings:

Figure 1 is a view of a filler form representing a capital letter of the alphabet of 50 the old English style, made of matted or felted cotton fiber held under compression by a binding agent in accordance with the present invention.

Fig. 2 is a corresponding view of a filler form as it would appear if unconfined by

either the binding agent or embroidery stitches, and

Figs. 3 and 4 are cross sectional views through corresponding portions of the forms shown in Figs. 1 and 2. 60

Figs. 5 and 6 are cross sectional views corresponding to Figs. 3 and 4 showing the filler form inclosed by embroidery stitches, Fig. 5 being a view with the filler held under compression by its binding agent and Fig. 65 6 a view as the same would appear when the binding agent is removed by washing.

In making embroidery filler forms in accordance with the present invention, a material is selected which will have an inherent 70 elasticity and expansibility, such, for example, as fine fiber felt or batting, specifically a sheet of felted fiber or cotton batting, of the desired thickness is provided from which the letters and designs may be 75 cut. This material is impregnated with a soluble binding agent which may be readily removed by washing in water or other liquid and the material held under compression while the binding agent is setting or drying 80 so that the form produced of the desired pattern will be thin and comparatively stiff although the interlocked fibers will cause it to retain its shape and prevent breakage by ordinary handling. The form so produced 85 is indicated at A in the drawings and in making use of the same it is attached to the base on which the embroidery is to be done by stitches or otherwise which may conveniently pass through small openings 90 formed in the filler form, whereby the filler form will be retained accurately in proper position. After being positioned on the embroidery base the embroidery is done in the ordinary way, to-wit, usually by embroidery stitches which pass over the filler form from side to side so as to completely inclose the same and produce in embroidery 95 the pattern of the filler form. After the embroidering is completed the binding 100 agent of the filler form is removed by washing or otherwise so as to permit the expansible material to expand as far as will be permitted by the confining embroidery stitches and the latter are thereby filled out 105 so as to give a well-rounded and highly pleasing appearance. In said drawings the appearance of the embroidery in the partially completed stage or before the filler form binding agent is removed is shown in 110

Fig. 5, and the appearance after the binding agent is removed is shown in Fig. 6.

By the employment of an expansible filler form of matted or felted fiber the parts of the same are retained in proper relation and the filler is kept within the embroidery stitches so that deterioration is unlikely even though the embroidery be subjected to repeated washings.

10 Furthermore the use of the binding agent gives a stiffened effect to the filler form which will permit it to serve as an effective guide for the needle during the embroidery process and this of itself is a material advantage, inasmuch as delicate lines and 15 tracery may be followed accurately and lateral displacement will be resisted even though the particular portion of the filler form being covered by the embroidery 20 stitches is of an exceedingly fine and delicate character.

Having thus described my invention, what I claim as new and desire to secure by Letters Patent is,—

25 1. A filler form for embroidery, consisting of an expansible fabric and an incorporated removable binding agent by which the fabric is stiffened and held under compression.

30 2. A filler form for embroidery, consisting of an expansible fibrous material and an incorporated soluble binding agent by which the fibrous material is held under transverse compression.

35 3. A filler form for embroidery, consisting of an inherently expansible and elastic fibrous material with the fibers matted together and an incorporated soluble binding agent by which the material is stiffened and held under transverse compression, said binding agent being removable by washing to permit the form to expand.

40 4. A filler form for embroidery, consisting of an expansible fibrous material and a starch binder which is soluble in water and by which the fibrous material is held under compression.

45 5. A filler form comprising a body of normally flexible expansible fabric compressed beyond its normal density and saturated by

a water soluble stiffening agent maintaining it in compressed condition, said material being capable of expansion to its normal dimensions and resuming its normal flexibility and fullness when said stiffening agent is washed out.

6. A filler form comprising a body of felt compressed beyond its normal density and saturated by a water soluble stiffening agent maintaining it in compressed condition, whereby said body is adapted to expand to its normal dimensions when said stiffening agent is washed out.

7. A filler form embodying an embroidery design comprising a body of flexible expansible fabric compressed beyond its normal density and saturated by a water soluble stiffening agent maintaining it in compressed condition, said fabric being capable of expansion to its normal dimensions and resuming its normal flexibility when said stiffening agent is washed out.

8. As a new article of manufacture, a filler form embodying an embroidery design comprising a body of compressed felt impregnated with a soluble stiffening agent.

9. A filler form embodying an embroidery design comprising a body of normally flexible, expansible and compressible fabric compressed beyond its normal density, and stiffened by means of a stiffening agent, said fabric being held in compressed condition by said stiffening agent and being capable of expansion when brought into contact with a cleansing fluid and resuming its normal thickness and flexibility.

10. A washable filler form embodying an embroidery design adapted to be completely covered by embroidery threads and comprising a flexible form body of unwoven fiber uniformly felted together, a removable toughening binder impregnating said form body and solidified throughout the fibers of the said form body from which it may be removed by washing in water.

DAVID A. ST. CLAIR.
